UNITED STATES PATENT OFFICE.

HERBERT E. SHREEVE, OF MILBURN, NEW JERSEY, ASSIGNOR TO WESTERN ELECTRIC COMPANY, OF NEW YORK, N. Y., A CORPORATION OF ILLINOIS.

TELEPHONIC APPARATUS.

1,130,029.

Specification of Letters Patent.

Patented Mar. 2, 1915.

Application filed January 14, 1913. Serial No. 741,930.

To all whom it may concern:

Be it known that I, HERBERT E. SHREEVE, a subject of the King of Great Britain, residing at Milburn, in the county of Essex 5 and State of New Jersey, have invented a certain new and useful Improvement in Telephonic Apparatus, of which the following is a full, clear, concise, and exact description.

10 This invention relates to telephonic apparatus and more particularly to a telephonic transmitting device.

The objects of this invention are to provide a new and improved telephone transmitter that will efficiently operate with the maximum range of sounds, will be free from the packing of the granulated resistance varying medium so detrimental in most forms of telephone transmitters, that will be 20 of few and simple parts and one that will maintain its adjustment under varying and trying conditions.

A transmitter made in accordance with this invention comprises generally a base 25 within which is a horizontally arranged granule containing chamber within which chamber is located a vertically movable electrode operatively connected with a diaphragm responsive to sound waves, said electrode being mounted to dip into comminuted conducting material in the granule containing chamber. The diaphragm may be mounted in any desired position so long as the chamber containing the resistance 30 varying medium is maintained in a substantially horizontal position.

In the drawings illustrating this invention,—Figure 1 is a vertical sectional view of a transmitter embodying this invention, 40 and Fig. 2 is a plan view of the transmitter with a part broken away.

Referring to the drawings 5 designates a main body portion of comparatively thick metal which will form a heat radiating element. This body portion is provided at its top with a screw threaded portion 6 adapted to receive a cap 7 and is provided on its lower portion with a recess 8. The said body portion is hollowed out to form a 45 chamber, the upper portion of which is conical in shape, as shown at 10, the larger end opening adjacent to the upper margin of the said body portion and the smaller end opening into a cylindrical portion 11 of said chamber. The cylindrical portion 11 of the 55

chamber is lined with an insulating lining 12 and contains comminuted conducting material 13. Located in the bottom of this cylindrical portion 11 of the chamber is a stationary electrode 15 connected with a 60 metal screw threaded stud 16 which extends through an opening 17 in the bottom of the body portion 5 and is provided with a clamping nut 18 for securing it in place and a terminal connecting nut 19. 65

Mounted upon the upper margin of the body portion 5 is a diaphragm 25 which is clamped thereon by means of the cap 7. Secured to the central portion of the diaphragm 25 is a downwardly extending stud 70 26 to the lower end of which is attached an electrode 27 having sloping side faces which may be either convergent or divergent at the lower end. The electrode shown is conical in shape and is arranged with its 75 end of larger diameter to dip into the comminuted conducting material 13 in the manner of a liquid transmitter. The electrode 27 is provided with an upturned edge 30, the purpose of which is to expose more surface 80 of the electrode to the resistance varying medium. An electrode of this shape, while exposing sufficient surface to the resistance varying medium to adequately conduct all of the current which is required, will by its 85 movement keep the whole body of comminuted material in such a state of agitation as to prevent its packing, and will also confine the current flow to the portion of the comminuted material which is subject- 90 ed to the greatest amount of agitation.

The cap 7 which is provided with a plurality of openings 35, 35 for the passage of the sound waves is parabolic so that all sound waves passing through the openings 95 in said cap will be deflected or concentrated upon the diaphragm.

The electrode 27 is electrically connected with the diaphragm 25 which is in electrical connection with the body portion 5. The 100 current conductors are connected, one with a binding screw 36 secured in said body portion, the other terminal being connected with the stud 16 connected with the stationary electrode. 105

As will be readily apparent from the description and the drawings, the device is one that may be easily and economically manufactured, one that is compact with all of the parts secured in a relation not easily 110

disturbed by jar incident to rough handling and usage, and one that is efficient in its operation.

Any of the comminuted material which is displaced from the portion 11 of the chamber due to the tipping of the device will by virtue of the sloping wall 10 be returned to the portion 11 when the device is again placed in position for use.

10 I claim—

1. In a telephone transmitter, comminuted conducting material and relatively movable electrodes, one of said electrodes being flat and supporting said comminuted conducting material and the other of said electrodes having sloping faces and being only partially in contact with said comminuted conducting material whereby the surface area of contact between said sloping-faced electrode and said comminuted conducting material is varied by the relative movement of said electrodes.

2. In a telephone transmitter, a main body portion having a chamber formed therein, comminuted conducting material in said chamber, electrodes in said chamber having a vertical movement relative to each other, one of said electrodes supporting said comminuted conducting material, the other being conical in form and having an upturned edge which dips into said comminuted conducting material.

3. In a telephone transmitter, a body portion having a chamber formed therein, comminuted conducting material in said chamber, movable and stationary electrodes in operative relation to said comminuted conducting material, a diaphragm operatively

connected with said movable electrode, and a parabolic sound concentrating device in operative relation to said diaphragm, adapted to receive and concentrate upon said diaphragm, sound waves from substantially all directions.

4. In a telephone transmitter, a main body portion having a chamber formed therein, comminuted conducting material in said chamber, movable and stationary electrodes in operative relation to said comminuted conducting material, a diaphragm operatively connected with said movable electrode and a parabolic cap having openings therein, said cap having screw threaded engagement with said body portion for clamping said diaphragm to said body portion. 55

5. In a telephone transmitter a body portion having a chamber formed therein, said chamber having a lower cylindrical portion and an upper conical portion, the larger end opening adjacent the upper margin 60 of said body portion, and the lower end opening into said cylindrical portion, comminuted conducting material in said cylindrical portion of said chamber, movable and stationary electrodes in operative relation to said comminuted conducting material, and a diaphragm secured to the upper margin of said body portion and closing said chamber. 65

In witness whereof, I hereunto subscribe my name this 11th day of January A. D., 1913.

HERBERT E. SHREEVE.
